DESIGN FOR A COMBINED BOTTLE AND CONTAINER

Marcel Leduc, Rochester, N. Y.

Application, December 5, 1944, Serial No. 116,713

Term of patent 3½ years

(Cl. D58—9)

To all whom it may concern:

Be it known that I, Marcel Leduc, a citizen of the United States of America, residing at Rochester, county of Monroe, and State of New York, have invented a new, original, and ornamental Design for a Combined Bottle and Container, of which the following is a specification, reference being made to the accompanying drawing, forming a part thereof and in which the figure is a perspective view of a combined bottle and container therefor showing my new design.

The side, back and top of the container portion, not shown, are ornamented in the same motif as the side and front shown.

The drawing is lined to indicate contrastingly colored areas.

I claim:

The ornamental design for a combined bottle and container, as shown and described.

MARCEL LEDUC.
